UNITED STATES PATENT OFFICE.

SAMUEL F. TOWNE AND NORMAN D. TOWNE, OF PHILADELPHIA, PENNSYLVANIA.

HAIR CURLER AND WAVER.

1,290,684.

Specification of Letters Patent.

Patented Jan. 7, 1919.

Application filed August 20, 1918. Serial No. 250,628.

To all whom it may concern:

Be it known that we, SAMUEL F. TOWNE and NORMAN D. TOWNE, citizens of the United States, residing at Philadelphia, county of Philadelphia, and State of Pennsylvania, have invented certain new and useful Improvements in Hair Curlers and Wavers, of which the following is a specification.

10 One object of our invention is to provide an improved hair curler and waver the body portion of which is made of fabric covered wires which are provided at their ends with flexible cushion tips of non-metallic material.

15 Another object of our invention is to so construct our improved hair curler and waver that the cushioned tips will be strong and durable and form a protection for the ends of the wires.

20 A further object is to so construct our improved hair curler and waver that it may be easily and freely inserted within the hair and will have no portions in which the hair will catch.

25 These objects, and other advantageous ends which will be described hereinafter, we attain in the following manner, reference being had to the accompanying drawings in which—

30 Figure 1 is a plan view of our improved hair curler and waver.

Fig. 2 is an enlarged fragmentary end view of the hair curler and waver shown in Fig. 1.

35 Fig. 3 is a view of similar nature to Fig. 2, showing one end in section.

Fig. 4 is a transverse section taken on the line 4—4 of Fig. 3.

40 Fig. 5 is a transverse section taken on the line 5—5 of Fig. 3.

Fig. 6 is a view of the hair curler and waver shown in Figs. 1 to 5, inclusive, before it is wrapped with a thread binding which forms a part of our invention.

45 Fig. 7 is a transverse section taken on the line 7—7 of Fig. 6.

Fig. 8 is a section taken on the line 8—8 of Fig. 6.

50 Fig. 9 is a section taken on the line 9—9 of Fig. 6.

Fig. 10 is a view of similar nature to Fig. 3 of a modified form of our invention,

Fig. 11 is a sectional view taken on the line 11—11 of Fig. 10, and

Fig. 12 is a sectional view taken on the line 55 12—12 of Fig. 10.

Referring to Figs. 1 to 9, inclusive, 15 and 16 represent two metallic wires which are twisted together in the direction of their length and are covered with a fabric covering 17. This fabric covering of each of the wires 15 and 16 consists of an outer layer 18 and an inner layer 19. The outer layer 18 is preferably made of interwoven or braided threads and thus a secure binding is provided 65 for the inner layer 19 and the wires 15 and 16. The wires 15 and 16 are preferably made of non-resilient flexible metal so that when bent they will retain the bent position.

In making the hair curler and waver as 70 illustrated in Figs. 1 to 9, inclusive, the opposite ends of the wires are cut off so that there is a portion of the fabric covering projecting beyond the ends of the hair curler and waver. This can be done by cutting off 75 the proper length of wires and then pushing the fabric covering back over the wires and cutting the desired amount off the ends of the wires. The fabric covering is then pulled into its normal position and in so doing 80 the cut ends of the wires are entirely covered by the opposite end portions of said fabric covering.

After this has been done the end portions of the fabric covering 17 are preferably saturated or coated with a water-proof glue or sizing. This coating or saturation can be done either by applying the glue or sizing to the end portions of the fabric covering or said latter end portions can be steeped or 90 dipped in the glue or sizing.

The threads of the fabric covering are then preferably twisted in the manner clearly shown in Figs. 3 and 6 of the drawings, and a cushion tip 20 is thus provided 95 which forms a tapered protecting cushion for the cut ends 21 and 22 of the wires 15 and 16. The end portions are then wound with a thread 23, said winding starting at a position within the length of the wires 100 15 and 16 and being continued over the cushion tip 20. If desired the thread 23 can be sized or coated with glue so that after the winding has taken place said thread will securely bind and maintain its 105 position, as illustrated in Figs. 1 to 5 inclusive. It will thus be noted that the thread 23 serves to bind the end portions of

the wires 15 and 16 together and also to bind together the twisted threads of the fabric covering 17.

It will be observed from Figs. 3 and 6 that a portion of the threads of the outer layer 18 of one wire covering serves to assist in binding certain of the threads of the inner layer 19 of the other wire covering. Thus adjacent ends of the fabric covering 10 of both of the wires are substantially integral and at the same time the advantage of having the two separate wires between the tips of the hair curler is maintained so as to permit free twisting and untwisting of 15 the convolutions of the body portion of the fabric covered wires.

A hair curler and waver thus formed can be easily inserted within the hair without injury to the scalp or to the hair and so 20 that no metal will come in contact with the head or hair. At the same time a secure binding is provided at the ends so that twisting and untwisting of the central body portion will not act to separate or break the 25 wires away from their binding. Further than this, a neat and comparatively smooth end binding is provided which has no portions in which the hair can catch or become lodged.

30 In Figs. 10 to 12, inclusive, we have shown a modification of our invention in which instead of pulling the fabric cover back over the ends of the wires and cutting off the 35 ends as above described in the form of our invention illustrated in Figs. 1 to 9, inclusive, the ends of the wires can be cut off abruptly and a wrapping 24 can be applied to the end portions of the fabric covered wires so that a portion 25 projects beyond 40 the cut ends 21^a and 22^a. This wrapping 24 can be made of tape or other flexible non-metallic material which can be pasted to the end portions of the fabric covered wires, after which a winding of thread 26 can be 45 applied in the same manner as above described in connection with the thread winding 23.

By winding the portion 25 with the thread 26 said portion 25 will become bunched and 50 will taper, as clearly shown in Fig. 10. The bunching of the portion 25 provides a cushion tip for protecting the end portions 21^a and 22^a of the wires. In this form of our invention we have indicated at 27 the fabric 55 covering for the wires 15^a and 16^a, these wires being twisted within their length in the same manner as described and illustrated in connection with Figs. 1 to 9, inclusive.

If the outer covering 17 is in the form 60 of a braid or other interwoven formation, a part can be raveled in order to permit a smooth twisting of the threads in the manner shown in Figs. 5 and 6.

While we have described our invention as 65 taking a particular form, it will be under-

stood that the various parts of our invention may be changed without departing from the spirit thereof, and hence we do not limit ourselves to the precise construction set forth, but consider that we are at liberty 70 to make such changes and alterations as fairly come within the scope of the appended claims.

Having thus described our invention, what we claim as new and desire to secure 75 by Letters Patent is:

1. A hair curler and waver including a wire having a non-metallic wrapped cushion tip forming a covering for the end of said wire, substantially as described. 80

2. A hair curler and waver including two wires twisted together within their length; and non-metallic flexible means wrapped around the adjacent end portions of said wires and projecting beyond said edge portions to provide outwardly tapering flexible cushion tips, substantially as described. 85

3. A hair curler and waver including two wires twisted together within their length; non-metallic flexible means surrounding the 90 end portions of said wires and projecting beyond said edge portions to provide an outwardly tapering flexible cushion tip; and a thread winding surrounding the end portions of said wires and the projecting 95 portion of said non-metallic flexible means, substantially as described.

4. A hair curler and waver including two fabric covered wires in which the ends of the wires are cut off within the length of the 100 fabric covering; and a binding for said wires, said binding being continued over the fabric covering beyond the ends of said wires, substantially as described.

5. A hair curler and waver including two 105 fabric covered wires in which the ends of the wires are cut off within the length of the fabric covering, said fabric covering, beyond the cut portion of said wires, being twisted; and a flexible binding for said 110 wires, said binding being continued over the twisted fabric covering beyond the ends of said wires, substantially as described.

6. A hair curler and waver including two 115 fabric covered wires in which the ends of the wires are cut off within the length of the fabric covering, said fabric covering, beyond the cut portion of said wires, being twisted; and a flexible binding for said 120 wires, said binding being continued over the twisted fabric covering beyond the ends of said wires, said binding consisting of a continuous thread wound around said fabric covering, substantially as described.

7. The process herein described of making 125 a hair curler and waver which consists in taking two fabric covered wires; then cutting off the end portions of the wires within the length of the fabric covering so as to permit a portion of said fabric covering to 130

- project beyond the cut ends of the wires; and finally binding the portions containing the ends of the wires, said binding extending around said projecting portions of the wire covering, substantially as described. 5
8. The process herein described of making a hair curler and waver which consists in taking two fabric covered wires; then cutting off the end portions of the wires within 10 the length of the fabric covering so as to permit a portion of said fabric covering to project beyond the cut ends of the wires; then twisting together the threads of said projecting portions of the covering; then applying glue or sizing to said twisted portions; and finally binding the portions containing 15 the ends of the wires, said binding also extending around said projecting portions of the wire covering, substantially as described.
9. The process herein described of making a hair curler and waver which consists in taking two fabric covered wires; then cutting off the end portions of the wires within the length of the fabric covering so as to 20 permit a portion of said fabric covering to project beyond the cut ends of the wires; then twisting together the threads of said projecting portions of the covering; then applying glue or sizing to said twisted portions; and finally binding the portions con- 25
- 30 taining the ends of the wires, said binding extending around said projecting portions of the wire covering, said binding consisting of wrapping a thread around said portions of the covering containing the ends of 35 the wires, said thread winding being continued around said projecting portions of the covering, substantially as described.
10. The process herein described of making a hair curler and waver which consists in taking two fabric covered wires; then pushing the fabric covering back over the ends of the wires; then cutting a certain portion off the ends of the wires; then returning the fabric covering to its normal position 40 so as to project beyond the cut ends of the wires; and finally binding the portion containing the ends of the wires, said binding also extending around said projecting portion of the wire covering, substantially as 45 described.
- 50

In testimony whereof we have signed our names to this specification in the presence of two subscribing witnesses.
